[57] CLAIM

The ornamental design for an art palette, substantially as shown and described.

DESCRIPTION

FIG. 1 is a perspective view of an art palette showing my new design;

FIG. 2 is a left rear bottom perspective view thereof;

FIG. 3 is an exploded front elevational view of the complete article on a reduced scale showing the relationship of the lid, cover and base;

FIG. 4 is an enlarged scale bottom plan view of the transparent lid;

FIG. 5 is a rear elevational view thereof;

FIG. 6 is a cross-sectional view taken along line 6—6 of FIG. 4;

FIG. 7 is an enlarged scale bottom view of the base section of the art palette;

FIG. 8 is a left side elevational view of the base section, the undisclosed right side elevational view being mirror image of the left side elevational view;

FIG. 9 is a rear elevational view of the base section, the undisclosed front elevational view being a mirror image of the rear elevational view thereof;

FIG. 10 is a top plan view of the base section;

FIG. 11 is a bottom plan view of the cover of the art palette;

FIG. 12 is a left side elevational view of the cover, the undisclosed right side elevational view being a mirror image of the left side elevational view;

FIG. 13 is a rear elevational view of the cover, the undisclosed front elevational view being a mirror image of the rear elevational view of the cover; and

FIG. 14 is a top plan view of the cover.
